(57) **CLAIM**

The ornamental design for a retrofit disc with slanted channels for a vehicle side washer, as shown and described.

DESCRIPTION

FIG. 1 is a perspective view of a retrofit disc with slanted channels for a vehicle side washer according to a first embodiment;

FIG. 2 is a side elevation view of the retrofit disc of FIG. 1, all the other sides being identical;

FIG. 3 is a top view of the retrofit disc of FIG. 1, the bottom view being identical; and,

FIG. 4 is a side elevation view of a stack of retrofit discs according to a second embodiment, each of the retrofit discs of FIG. 4 being identical to the retrofit disc of FIGS. 1 through 3.

The broken lines illustrate portions of the retrofit disc for a vehicle side washer and form no part of the claimed design.
